UNITED STATES PATENT OFFICE

140,652

DESIGN FOR A STORAGE CABINET FOR TOYS

John H. Coller, South Bend, Ind.

Application August 14, 1944, Serial No. 114,879

Term of patent 7 years

(Cl. D33—19)

To all whom it may concern:

Be it known that I, John H. Coller, a citizen of the United States, residing at South Bend, in the county of St. Joseph, State of Indiana, have invented a new, original, and ornamental Design for a Storage Cabinet for Toys, of which the following is a specification, reference being had to the accompanying drawing, forming part thereof.

Fig. 1 is a perspective view of a storage cabinet for toys, showing my new design.

Fig. 2 is a perspective view thereof as the design appears with the doors in open position.

I claim:

The ornamental design for a storage cabinet for toys, as shown.

JOHN H. COLLER.
